UNITED STATES PATENT OFFICE.

JOHN BAER, OF TORONTO, ONTARIO, CANADA.

ELEVATOR LOCK.

Application filed July 1, 1921. Serial No. 481,894.

To all whom it may concern:

Be it known that I, JOHN BAER, a subject of the King of Sweden, and resident of 145 Tecumseh St., in the city of Toronto, county of York, Province of Ontario, in the Dominion of Canada, have invented certain new and useful Improvements in Elevator Locks, of which the following is a specification.

10 The invention relates to improvements in elevator locks as described in the present specification and shown in the accompanying drawings that form a part of the same.

15 The invention consists essentially of the novel features of construction whereby the electrical circuit through the control mechanism is closed upon the closing of the elevator door and is automatically opened upon the opening of said elevator door.

20 The objects of the invention are to eliminate all possibility of accidents due to movement of the elevator while the door is in its open or partly open condition, to provide a form of lock which may be readily 25 installed on elevators already in use, and generally to provide a form of elevator lock which will be inexpensive of construction, efficient in operation and durable.

30 In the drawings Figure 1 is a view of a portion of the elevator shaft showing a portion of the door and the breaker box.

Figure 2 is a vertical sectional view taken on the line A—A of Figure 1.

35 Figure 3 is a view of a portion of an elevator shaft showing a modified form of device adapted for use in cases where the doors are of the swinging type.

Figure 4 is a vertical sectional view taken on the line B—B of Figure 3.

40 Figure 5 is a detail.

Like numerals of reference indicate corresponding parts in the various figures.

Referring to the drawings 1 represents the wall of the elevator shaft into which are 45 fitted the door sections 2 and 3 as customary, the top section of said door being provided with a projecting finger 4.

50 5 is a casing rigidly mounted on the wall 1 adjacent to the door section 2 and constituting a container for the various parts of the circuit control mechanism to be described hereinafter, said box being provided with any convenient form of door.

55 6 is a locking bar or bolt horizontally mounted in bearings 7 and 8 in the walls of the box 5 and being held normally to its

extended position in the path of the finger 4 by means of a helical spring 9 encircling said bolt between a shoulder 10 thereon and the wall of the box, said bolt being manually 60 withdrawable by means of a lever 11 pivoted to the outer end of said bolt and fulcrumed in a bracket 12 projecting outwardly from the box 5.

13 is a block constructed of any suitable insulating material and being rigidly mounted on the rear wall of the casing 5 beneath the bolt 6, said block being provided with vertical bores into each of which is fitted a metal bushing 14 adapted to slidably 70 accommodate a contact plug 15.

16 are the electrical wires leading from the control mechanism (said mechanism not being shown in the drawings as same may be of any well known type) and extending into the bushing 14 respectively, the ends of said wires and the top ends of the contact plugs 15 being spaced by springs 17 disposed therebetween.

18 is a shaft rotatably mounted in bearings 19 and 20 in the casing 5 and having a roller 21 rigid therewith, said roller being located just below the casing 5 and forming a support for the contact plugs 5 but preferably being offset slightly from said plugs, said roller being constructed of insulating material and having a comparatively narrow strip 22 of current conducting material set therein and adapted upon the rotation of said roller to be engaged by said plugs for completing the circuit through the control mechanism.

The bearing 20 is preferably a loose bearing exteriorly threaded and adapted to be rigidly secured in the comparatively large opening through the box 5 by means of a nut 23 screwing thereover and drawing the flanged outer end of the bearing tightly into engagement with the wall of the casing, this construction being desirable to permit of inserting the shaft and roller into the casing.

24 is an arm rigidly mounted on the outer end of the shaft 18 and carrying at its outer end a roller 25.

26 is a metal strap mounted on a block 27 on the lower section of the door, said strap being turned inwardly towards the door at a comparatively sharp angle and in the meeting position of the door sections 110 substantially engaging the top section of the door, said strap or plate being adapted on

the upward movement of the lower section of the door to deflect the roller 25 and the arm 24 outwardly thus rotating the roller 21 and bringing the inset 22 of conducting material into engagement with the contact plug 15 and thus completing the electrical circuit through the control mechanism upon the arrival of the door sections to their meeting positions. Upon the receding of 5 the strap 26 due to the separating of the door sections the arm 24 is allowed to drop to a vertical position rotating the roller 21 and disengaging the metal inset 22 from the plugs 15 and breaking the circuit 10 15 through the control mechanism coincident with the opening of the door.

In Figures 3 and 4 a modified form of construction is shown for use in cases where doors of the swinging type are employed, 20 under which circumstances a casing 5 containing a block 10 containing bushings 14, contact plugs 15, wires 16 springs 17 and roller 21 having an operating arm 24 identical with the construction described above 25 is located above the respective door sections 28 and 29, each of said sections having a block 30 mounted thereon on which the roller from the corresponding arm 21 rests when the door section is closed, thus holding 30 the metal inset 22 of the roller 21 in engagement with the plugs 15 and closing the circuit through the control mechanism when both door sections are closed. When one or

other of the sections 28 or 29 are swung open away from the arm 24 said arm drops 35 down to a vertical position and disengages the contact member 22 from the plugs 15 and opens through the control mechanism making it impossible to operate the elevator when either of the door sections are open. 40

What I claim is:—

In elevator locks for two members movable in relation to one another, an electric safety device and mechanical means for operating the same comprising a cam fixedly 45 secured to one member and formed with an inclined riding surface, an electric contact inserted lengthwise in an insulated block made in the form of a roller and journaled in the other member, an arm extending 50 from said contact roller and carrying a roller at the end thereof riding on said inclined surface and a plurality of electrical contacts slidably supported and spring-held in contact with said contact roller and permanently connected to an electric operating circuit and forming a switch mechanism actuated to make or break the electric circuit on the movement of a member aforesaid. 55

Signed at the city of Toronto, this 17th day of June, 1921.

JOHN BAER.
